(57) **CLAIM**

The ornamental design for a steering wheel lap attachment, as shown and described.

DESCRIPTION

Phantom lining, where utilized, is for illustrative purposes only, and is not intended to limit the claimed component design to the features shown in phantom.

FIG. 1 is a top plan view of a steering wheel lap attachment showing our new design;

FIG. 2 is front elevational view thereof;

FIG. 3 is a right side elevational view, the left side elevational view being a mirror image thereof;

FIG. 4 is a rear elevational view thereof; and,

FIG. 5 is a bottom plan view thereof.
